UNITED STATES PATENT OFFICE.

MAURICE P. SCHWARTZ, OF INDIANAPOLIS, INDIANA, ASSIGNOR OF ONE-HALF TO
HERMAN A. HELMING, OF INDIANAPOLIS, INDIANA.

DRUGGIST'S CABINET.

946,467.

Specification of Letters Patent. Patented Jan. 11, 1910.

Application filed May 22, 1909. Serial No. 497,736.

To all whom it may concern:

Be it known that I, MAURICE P. SCHWARTZ, a citizen of the United States, residing at Indianapolis, in the county of Marion and 5 State of Indiana, have invented certain new and useful Improvements in Druggists' Cabinets, of which the following is a specification.

It is frequently the case that dealers in 10 articles of the kinds commonly contained in small packages lack sufficient shelf room to properly place all their goods. This is particularly true in retail drug stores; where, in many cases, the druggist has only 15 a small sales room, but must, necessarily, keep a very large number of articles in stock in order to have on hand a complete assortment. Then, too, in such cases it is very difficult to have all the stock accessible,—many articles being hidden behind others, so as to be found only after a considerable search, unless the salesman has 20 a complete memory of the location of all the articles.

25 The object of my said invention is to produce a cabinet which will conveniently contain a much larger number of articles than ordinary shelving, and so arranged that the entire number may be easily brought 30 into view, thus not only very greatly economizing space, but rendering the articles much more conveniently accessible and easily found. The arrangement includes a system of labeling and indexing, which 35 enables the recently-employed salesman, having no memory knowledge of the stock, to find any article desired with facility.

Referring to the accompanying drawings, which are made a part hereof, and on which 40 similar reference characters indicate similar parts, Figure 1 is a perspective view of a fragment of a cabinet embodying my present invention; Fig. 2 a detail sectional view as seen when looking in the direction indicated by the arrows from the broken line 2 2 in Fig. 3; Fig. 3 a detail horizontal sectional view as seen when looking downwardly from the broken line 3 3 in Fig. 2; Fig. 4 a detail perspective view showing 45 the form, arrangement and method of attaching the guiding pins which control the position of the individual cabinet boxes or containers, and Fig. 5 a detail sectional view

at the point indicated by the broken line 5 5 in Fig. 3.

As shown in the drawings this cabinet 55 consists of a series of suitably supported shelves 21 having grooves 22 and 23 in their upper and lower surfaces extending transversely thereof from the rear to near the 60 front sides, and a series of cabinet boxes or goods containers 31 placed between said shelves and having guiding pins 32 and 33 extending into said grooves in the shelves. As shown in Fig. 1 the several cabinet boxes 65 31, when in normal position, occupy the entire space between the shelves longitudinally thereof, except that the bodies are spaced slightly apart back of the fronts to accommodate guides which I prefer to use. When 70 access is desired to the contents of any one of these boxes, it is first drawn out until its rear end is in front of the normal position of its front end (one of the boxes in the upper row is indicated in this position in 75 Fig. 1), and then swung around sidewise to the position in which one of the boxes in the lower row is shown, bringing the open side thereof to the front, and completely exposing its contents. The shelves 21 are sufficiently wider than the length of the cabinet box 31, so as to form a ledge in front of the row of boxes, upon which the individual box when drawn out may rest as shown. The 80 grooves 22 and 23, in which the pins 32 and 33 rest and operate, stop a little short of the front edge of the shelf 21, so that the boxes 85 cannot be completely withdrawn from their proper positions.

As shown in Figs. 3 and 5, I have placed 90 between the bodies of the cabinet boxes, or containers, just back of the front ends thereof, guide pins 29, and these I preferably surround with small anti-friction rollers 39. These guide pins prevent the front ends of 95 said boxes or containers from moving sidewise into the space left vacant when one of said boxes is withdrawn, in use, and this greatly facilitates the certain and ready insertion of such box or container to its at-rest 100 position.

Each of the cabinet boxes should be provided with a handle 34, by means of which it may be easily moved in and out, and is also provided with a label holder 35, upon 105 which may be inscribed the names of the

- various articles which the box contains. The boxes should also be each one given a number, so that they can be readily identified by means of a suitable card or other index.
- 5 Each box may be divided into two or more compartments by suitable shelves, as 36, and suitable retaining devices for the articles to be placed therein as 37, and 38 may also be used.
- 10 Having thus fully described my said invention, what I claim as new, and desire to secure by Letters Patent, is:—
1. The combination, in a cabinet, of a series of shelves having grooves in their upper 15 and lower surfaces extending transversely thereof to near their front edges, and containers shorter than the width of the shelves mounted thereon and having pins which engage with the grooves, said pins being arranged to stop the movement of the containers when pulled outwardly and prevent complete disengagement thereof with the shelves, and said containers being also adapted to swing on said pins as a pivot after being pulled out to the predetermined distance
- and thus brought around so that the contents thereof will be exposed and conveniently accessible.
2. The combination, in a cabinet, of a series of shelves having transverse grooves 30 in their upper and lower faces, containers placed between said shelves and having pins extending upwardly and downwardly therefrom and engaging with the grooves in the shelves, said containers being thereby held to position and permitted to be pulled out 35 and swung around to enable access to their contents, and guides arranged between the sides of the containers whereby they are kept from sidewise displacement when in 40 closed position.

In witness whereof I, have hereunto set my hand and seal at Indianapolis, Indiana, this nineteenth day of May, A. D. one thousand nine hundred and nine.

MAURICE P. SCHWARTZ. [L. S.]
